UNITED STATES PATENT OFFICE.

FRANK J. HERRICK, OF NEW BRITAIN, CONNECTICUT, ASSIGNOR TO THE
NORTH & JUDD MANUFACTURING COMPANY, OF SAME PLACE.

DESIGN FOR A BELT-CLASP.

SPECIFICATION forming part of Design No. 20,141, dated September 9, 1890.

Application filed April 24, 1890. Serial No. 349,399. Term of patent 7 years.

To all whom it may concern:

Be it known that I, FRANK J. HERRICK, a citizen of the United States, residing at New Britain, in the county of Hartford and State 5 of Connecticut, have invented and produced a new and original Design for Belt-Clasps, of which the following is a specification, reference being had to the accompanying drawing, forming a part thereof.

10 The figure is a detail front view of a belt-clasp, showing my design.

The leading feature of my design consists of the link *a*, that extends between the loops or side parts of the belt-clasp and is of diamond shape. This shape may be represented by the outline of the bounding edges of the link, whether the same is solid or is composed of a frame-like structure.

15 As a minor feature of the design, the loops

b and *c*, between which the link extends, are 20 oblong in outline, usually with the ends rounded, as shown, the surface of the frame-like body part of the loop being formed to present the appearance of a succession of diamond figures extending completely around the 25 loop.

What I claim is—

The design for a belt-clasp herein shown and described, the same comprising the oblong frames with their surfaces shaped to represent a surface of diamond figures, and a diamond-shaped link extending transversely between the two loops, all substantially as described and shown.

FRANK J. HERRICK.
